UNITED STATES PATENT OFFICE.

LYMAN C. JOSEPHS, JR., OF ALLENTEWON, PENNSYLVANIA, ASSIGNOR TO INTERNATIONAL MOTOR COMPANY, OF NEW YORK, N. Y., A CORPORATION OF DELAWARE.

CONTROL MEANS FOR THROTTLE VALVES AND THE LIKE.

Application filed February 25, 1925. Serial No. 11,617.

Means for operating the throttle valve of an internal combustion engine by other than direct connected linkage to a manually operable lever, have received some consideration. 5 For certainty of operation, nicety of adjustment and complete facility of control power means, if satisfactory, are preferable to manual means, particularly under some circumstances. In the control of motors for rail cars, for instance, it is believed that power means are virtually necessary to control the engine speeds in a way which will be fully satisfactory. Such power means might assume different forms, that illustrated herein 10 being electro-pneumatic. Such means are characterized by extreme simplicity of construction and arrangement of parts, compactness, certainty of operation, and nicety of control. In the design shown in the drawings, 15 for instance, it has been found possible to provide for eight gradations of speed, that is eight settings for the throttle valve with the use of only three electro-magnets each of which magnets has only a single lead wire and 20 a ground.

As the description proceeds, however, it will be evident to one skilled in the art that the invention is not limited to the particular form or arrangement of parts nor the wiring 30 or the magnets. In the drawings:

Figure 1 is a view in side elevation of an improved electro-pneumatic control showing its mounting in operative relation to the throttle valve of an internal combustion engine. 35

Figure 2 is a view in end elevation thereof.

Figure 3 is a view on an enlarged scale partly in section and partly in elevation through the air cylinder and taken on the 40 plane indicated by the line 3-3 of Figure 1 and looking in the direction of the arrows.

Figure 4 is a view in horizontal section through the same controlling devices taken on the plane indicated by the line 4-4 of Figure 1.

Figure 5 is a schematic projection of a suitable controller drum by which eight speed gradations may be accomplished.

Without in any way intending to limit the 50 invention to the particular location of the devices with reference to the controlled element and the support for it the drawings

show a construction which might be suitable, for instance, in a rail car which is propelled by an internal combustion engine. As shown 55 in Figures 1 and 2 the motor casing *a* may carry a suitable bracket *b* to which is bolted a self-contained power controlling means for the throttle valve lever *c* by which the flow of mixture is controlled. As indicated in Figure 3 bolts *d* may pass through the bracket *b* and the walls *e* of the air cylinder to afford substantial support for both the air cylinder and the electro-magnets *f*, *g* and *h*, by which the movement of the various air valves is 60 initiated as will appear hereinafter. Bolts *g'*, *f'* and *h'* serve to secure the frames of the electro-magnets to the walls *e* of the air cylinder. It will be seen from Figure 4 that the electro-magnets *f*, *g*, may be mounted conveniently at one side of the air cylinder while the third electro-magnet *h* may be mounted at the opposite side and staggered with respect to the two first named electro-magnets. 65 The entire arrangement of parts is simple and 70 compact and the units may be readily assembled and disassembled either as a whole, through removing the bolts *d* or in part, as 75 by removing any one of the bolts *f'*, *g'*, *h'*.

The invention is addressed particularly to 80 the provision of means operated pneumatically for moving the controlled element (which in the illustrated embodiment is the lever arm *c* of the throttle valve) from zero position to a plurality of other positions so 85 as to give gradations of speed and to hold the throttle valve in any one of such other positions with an extreme nicety of control. In the preferred embodiment it is proposed, in addition, to control the air valve by electrical 90 means so that the operator may, through a suitable controller, initiate operation of any one or more of the air valves to bring about selectively the desired positioning of the 95 throttle valve.

As shown in Figures 1 and 4 the lever arm *c* of the throttle valve is connected pivotally through a slot *i* to a push rod *k* which extends through a threaded head *e'* within the end of a cylinder sleeve *e* and is normally maintained in retracted position by a spiral spring *l* within the cylinder sleeve. This position 100 may be referred to as the "zero" position of the throttle valve at which the engine speed

is the lowest. Pneumatic means are provided to move the push rod k against the action of the spring l towards the left as viewed in Figure 4 thereby swinging the throttle lever c to positions in which the speed of the motor will be increased. Such means in one embodiment consist essentially of a plurality of movable piston sections within the cylinder sleeve e^2 and means to admit air in such relation to such piston sections as to move one or more of them selectively and thereby force the push rod k towards the left as viewed in Figure 4. Commencing at the right end of the view shown in Figure 4 there will be observed a piston section m carrying a packing m' which engages the walls of the sleeve, and an air port e^3 through which air may be admitted to move the said piston section m towards the left against the action of the spring l . The piston m is of annular form and carries a pin m^2 which extends through a slot n in an abutment n' which is shouldered to limit the movement of the piston m towards the right. This abutment n' is permanently fixed within the cylinder head e^4 . The slot n determines the length of travel of the piston section m towards the left and the slot is made intentionally of predetermined length depending upon the range of travel desired for the throttle lever c under impetus of the piston section m .

Beyond this piston section m are provided two opposed piston sections o and p whose ends normally abut under the influence of the spring l . The piston section o has a packing o' and the piston section p has a packing p' both engaging the walls of the cylinder sleeve e^2 . These two sections, in addition, carry pins o^2, p^2 which extend through a slot q in a link q' , the length of the slot determining the range of movement of the pistons o, p , with respect to one another when air is introduced therebetween through a port e^5 . Relative movement between the piston section m and the piston section o is prevented by a spacing ring r .

Another pair of piston sections s, t , are disposed within the cylinder sleeve e^2 beyond the sections o, p . These sections have packings s', t' , and carry pins s^2, t^2 , respectively, and the pins extend through a slot u formed in a link u' , the length of the slot determining the extent to which the piston sections may be separated when air is introduced therebetween through an air port e^6 . A spacing ring r' floats between the piston section p and the piston section s and prevents relative movement therebetween. The piston section t is in operative engagement with the end k' of the push rod k which is of annular form in the interest of compactness and proper relationship of parts.

In practice, it may be desirable to move the controlled element by equal gradations and to accomplish this the slot q in the link q' is of

such length as to permit a total relative movement between the piston sections o, p , equal to twice the travel of the piston section m , as determined by the length of the slot n . Similarly, the slot u in the link u' is of such length as to permit separation of the piston sections s, t , by a distance equal to four times the piston travel of the section m . The relationship of parts is such that the spring l maintains all of the elements in abutment so that when air is admitted through the port e^3 , for instance, the piston section m is propelled towards the left and its movement is transmitted through the ring r , piston sections o, p , ring r' , and the piston sections s, t , to the push rod k . When air is admitted through the port e^5 between the piston sections o, p , the section o is backed up by the ring r and the piston section m and abutment m' so that it cannot move while the other section p is propelled towards the left and its movement is transmitted through the ring r' and the piston sections s, t , to the push rod k . Similarly, when air is admitted through the port e^6 the piston section s is held against movement since it is backed up by the ring r' , piston sections o, p , ring r , piston section m and abutment m' , the section t being free to move away from the section s and transmit its motion directly to the push rod k . By admitting air through any two of the ports simultaneously or through all three of them simultaneously the total distance through which the push rod k is moved will be equal to the additive amount of movement of the pistons selected.

Means for controlling the flow of air into the cylinder consists in electro-magnets each having armatures carrying air valves controlling the admission of air through the respective ports e^3, e^5 and e^6 , and the exhaust of air therefrom. Figure 3, shows a suitable arrangement of air channels and control therefor with respect to the electro-magnet h by which the admission and exhaust of air through the port e^5 is controlled. Air enters the cylinder wall e from a suitable source of compressed air through a passage e^7 which leads to a valve chamber e^8 within which is disposed an inlet valve v . This valve may be normally held on its seat by a spring v' . The chamber e^8 communicates, under the control of the valve v with an inlet channel e^9 which terminates in the port e^5 . When the valve v is seated obviously the air supply is cut off from the port e^5 but air within the cylinder sleeve e^2 may exhaust therethrough past a valve v^3 which is carried on the same stem with the valve v . The exhaust port which may lead to the atmosphere is indicated at v^2 . The valves v, v^3 , are in turn carried on a stem w supported by an armature w' of the electro-magnet h . When the electro-magnet h is energized the throttle will be held positively in the position predetermined by the

extent of travel of the piston section p under the influence of the air supply back of this piston section. When the electro-magnet h is de-energized the spring v' will cause the 5 valve v to seat and simultaneously cause the valve v^3 to move from its seat so that air may be exhausted through the port e^5 and the piston section p moved into abutment with the other section o under the influence of the 10 spring l . The other magnets f and g are similarly associated with air valves to control the admission and exhaust of air through the respective ports e^3, e^5 . A further description of them is unnecessary. Electrical connections for the magnet h may include a ground wire such as h^2 and a lead wire h^3 which may be connected with the contacts of a suitable controller, the projection of which is illustrated diagrammatically in Figure 5. The 15 contacts for the electro-magnet h are indicated by the reference characters h^4 , the contact for the electro-magnet g is indicated at g^2 , and the contacts for the electro-magnet f are indicated at f^2 . The controller is also 20 grounded so that three lead wires serve to bring about the control of the respective electro-magnets.

A full appreciation of the gradations possible may be appreciated by reference to Figure 5. When all three magnets are grounded 25 the controlled element may be assumed to be in zero position. The various positions taken by the controller in its movement to control the actuation of the different ports have been indicated at the left of Figure 5 where the numerals 0 to 7 indicate such positions. The numeral 0 represents the neutral or zero position. The first movement of the controller to position No. 1 energizes the electro-magnet f by means of contact f^2 . The next movement to position No. 2 energizes the electro-magnet h alone by means of contact h^4 . The next movement to position No. 3 energizes the electro-magnet f and the electro-magnet h by 30 means of the contacts f^2 and h^4 . The next movement to position No. 4 energizes the electro-magnet g alone by means of the contact g^2 . The fifth movement to position No. 5 energizes the electro-magnets f and g by 35 means of the contacts f^2 and g^2 . The sixth movement to position No. 6 energizes the electro-magnets h and g by means of the contacts h^4 and g^2 and the seventh movement to position No. 7 energizes all three of the 40 electro-magnets by means of the contacts f^2, h^4 and g^2 . If the piston movements, as suggested, are designed to bear the relation of 1, 2 and 3, it will be understood that the controller selection given brings about seven 45 equal gradations above zero in arithmetical progression corresponding to the movements of the controller just described and the throttle valve is held in any one of these seven positions by a simple operation of the controller by the driver, the seven positions of

the controller representing variations in the opening of the throttle valve from a fully closed position corresponding to zero position of the controller and indicated as 0 at the right-hand side of Figure 5 through one-eighth, one-fourth open, etc. as indicated by the several fractions to fully open position indicated by the fraction seven-eighths.

The parts described are compact, simple in construction and assembly, easy of access 75 for replacement or repair and give a much nicer degree of control than can be brought about by a manually operable controlled element. The successive positions of the controlled element are eight determined with 80 mathematical exactness and do not admit of any variation.

It will be understood that changes in form and arrangement of parts may be made and that other elements than a throttle valve may 85 be controlled.

What I claim is:

1. A pneumatic controlling device including an air cylinder, a plurality of movable piston sections each mounted slidably therein, a fixed abutment at one end of the cylinder to limit the movement of the piston sections in one direction, lost motion connections between the piston sections including hollow portions in each piston, pins mounted across 90 the hollow portions and a link with slots to engage the pins, and means for moving the sections additively.

2. Electro-responsive pneumatic controlling means including an air cylinder, five movable piston sections therein, the controlling ports of which are controlled by three separate means, controller means to actuate said means in desired combinations, and means whereby seven positions of said piston 105 sections may be effected through operation of the controller.

3. Electro-responsive controlling means including an air cylinder, five movable piston sections therein, a control port for one of 110 said pistons, a control port for two other pistons, a control port for the other two pistons, means to control the movement of said pistons in one direction, means to limit the movement of the pistons to predetermined 115 degrees respectively, in the opposite direction, valves to control said control ports respectively, and separate electro-responsive means to actuate said valves respectively, and means to progressively energize said electro-responsive means to effect in predetermined manner the selection of said piston sections.

4. Electro-responsive controlling means including an air cylinder, five movable piston sections therein, a control port for one of said 120 pistons, a control port for two other pistons, a control port for the other two pistons, means to control the movement of said pistons in one direction, means to limit the move- 125

ment of the pistons to predetermined degrees respectively in the opposite direction, valves to control said control ports, respectively, separate electro-responsive means, a controller, said electro-responsive means comprising three electro-magnets each having a ground wire and a lead wire to controller contacts

and means whereby seven positions of said piston sections may be effected through operation of the controller.

This specification signed this 11th day of February, A. D. 1925.

LYMAN C. JOSEPHS, JR.
